UNITED STATES PATENT OFFICE

EARL C. WALKER, OF CHICAGO, AND GUSTAF W. ENGSTROM, OF RIVERSIDE, ILLINOIS,
ASSIGNORS TO INTERNATIONAL HARVESTER COMPANY, A CORPORATION OF NEW
JERSEY

BURNER

Application filed May 31, 1930. Serial No. 457,947.

This invention relates to a burner for hydrocarbons. More specifically it relates to an improved construction for a vaporizing fuel burner adapted to utilize low grade liquid hydrocarbons.

An object of the invention is to provide an improved construction which is comparatively simple and economical to build, and which is efficient and durable in operation.

10 A more specific object is to provide a vaporizing chamber for liquid fuel burners which will withstand the wide variations in temperature to which it is subjected.

Another object is to provide means for 15 preheating the main burner by a pilot burner.

Another object is to provide means for controlling the air admitted to the main burner and to the pilot burner.

20 These and other objects, which will be apparent, are accomplished by the construction and operation of a burner as will be fully explained in the following detailed description.

In the drawings:

25 Figure 1 is a plan view of the burner of this invention;

Figure 2 is a sectional view on the line 2—2 of Figure 1;

Figure 3 is a sectional view taken on the 30 line 3—3 of Figure 1; and

Figure 4 is an enlarged view showing the details of the burner control.

Only such portions of the burner are shown as are necessary to show the novel features 35 of the device. A housing consisting primarily of a substantially cylindrical portion 1, and a slightly conical bottom portion 2 encloses the pilot burner and the lower portion of the main burner. A pair of vaporizing 40 members formed as question-mark shaped castings 3 substantially fill the housing 1 in spaced relation to the walls and bottom thereof. The casings 3 are oppositely curved and have the curved portions lying adjacent 45 each other in spaced relation, as clearly shown in Figure 1. On the upper horizontal face the castings are provided with substantially semi-circular openings 4 which lie in a substantially circular area.

50 A base plate 5 substantially annular in

shape is provided with a diametrically extending partition 6. Said partition forms with the remainder of the plate two semi-circular openings. The plate is placed over the adjacent curved portions of the castings 3 55 with the openings therein in alignment with the openings 4 in the tops of the castings. Apertured ears 33 formed on the partition 6 provide means for securely clamping the base plate to similar ears 34 formed on the castings 3 by means of bolts 35.

At the centers of the arcuate portions of the base plate 5 ears 36, similar to the ears 33, project inwardly and are in alignment with ears 37 formed on the castings 3, one of 60 which can be seen in Figure 3. Bolts 38 secure the ears 36 and 37 together. The partition 6 is wide enough to bridge the space between the adjacent curved ends of the castings 3 and overlie the upper parallel edges of 65 the castings along the openings 4.

An annular ring 39, having integral outwardly projecting ears 40, is positioned above the base plate 5. Cap screws 41, extending through the ears 40, are threaded into bosses 70 42 formed on the base plate 5, thereby holding the ring 39 securely in position. A series of spaced rings 32 are secured to the ring 40 by rods 43 passing through the rings. A conical downwardly projecting member 44 75 over the top of the rings, is also secured in position by the rods 43. The rings form a burner grating of a type well known in the art.

Opposite the curved ends, the castings 3 80 are provided with substantially parallel extensions 7, which are provided with apertured lugs 8 for attachment to a supporting plate 9. The plate 9 is secured to the housing 1. Openings 10 in the plate 9 register with the 85 open ends of the castings 3. A fuel and air supplying conduit 11 is secured to the plate 9. The conduit 11 is flattened at the end adjoining the plate 9 and is provided with a vertical partition 12. The conduit 11 is 90 flanged to mate with a corresponding flange on an air supply pipe 13. Air under pressure from a fan is supplied through the pipe 13. A butterfly valve 14 is mounted on a shaft 15 95 in the circular portion of the conduit 11. 100

The valve is somewhat oval in shape so that the conduit 11 will be substantially closed when the valve 14 is in an angular position, as shown in Figure 1. An adjustable stop 5 16 is provided to limit the closing action of the valve 14. An air off-take 17 is attached to the conduit 11 on the air inlet side of the valve 14. The off-take 17 connects with a pipe 18 which leads to a pilot burner positioned below the main burner. The pilot burner is mounted on the bottom 2 of the housing surrounding the lower portion of the main burner. The pilot burner consists essentially of a small vaporizing chamber 19 to which the inlet pipe 18 is connected and a grating 20 above the chamber 19. Provision is made below the vaporizing chamber 19 for an electric heating coil for preliminary vaporization. A fuel 10 nozzle 31' projects into the connection between the pipes 17 and 18 for supplying fuel to the pilot burner.

A butterfly valve 21 mounted on a shaft 22 is provided in the air off-take 17 leading to the pilot burner. As best shown in Figure 4, the valves 14 and 21 are operatively connected together. A lever 23 secured to the shaft 15 is pivotally connected to a link 24, which is in turn pivotally connected to a lever 25. The lever 25 is rigidly connected to the shaft 22 of valve 21. A series of holes 26 in the end of the lever 25 provides means for adjusting the relative positions of the valves 14 and 21.

35 A lever 27 is also rigidly connected to valve shaft 15. A solenoid 28 is mounted adjacent the conduit 14 and is adapted to operate the air control valves. An extension 29 from the solenoid plunger, not shown, is operatively connected by a link 30 to the lever 27. A link 45, pivotally connected at one end to the lever 27 intermediate its ends, is pivotally connected at its other end to the plunger 46 of a dash pot 47. The dash pot may be of 40 any conventional construction, being utilized to provide for smooth operation of the valves.

Oil under pressure is supplied for the main burned through a pair of fuel nozzles 31 extending through the walls of the conduit 19 50 from opposite sides thereof in a position to be substantially centrally located with respect to the openings 10 in the plate 9 leading to the respective castings 3.

In the operation of this burner, air is supplied under pressure through the inlet pipe 13. The pilot burner is normally maintained in operation continuously, fuel oil being supplied through the nozzle 31' and air through the pipes 17 and 18. The relative position 55 of the valve 21 controlling the air delivering to the pilot burner with relation to the valve 14, which controls the air supplied to the main burner is such that, when the valve 14 is completely closed, the valve 21 remains 60 opened a sufficient amount to supply the nec-

70 essary amount of air to the pilot burner. It will be understood that, when the main valve 14 is closed, the pressure in the air supply pipe 13 will be much higher than when the valve 14 is open. It is, therefore, necessary to have the two valves connected together in such a manner that, as the valve 14 is opened, thereby reducing the pressure of the air supply, the valve 21 will also be opened to lessen the resistance in the off-take 17 and to supply a sufficient amount of air to the pilot burner to maintain its continuous operation. It is also necessary that air may not be supplied to the pilot burner at too high a pressure, as, in that case, the burner might be extinguished by the excess pressure.

75 Fuel is supplied under the desirable pressure to the nozzles 31 and to the fuel nozzle 31' in the off-take 17 leading to the pilot burner. The atomized oil is carried along with the air stream through the castings 3 which serve as vaporizing chambers for the oil. The two streams of combustible mixture are delivered vertically through the openings in the top of the castings 3, and the homogeneous mixture is delivered through the burner grating 32, after which combustion takes place.

80 It is to be understood that this invention relates particularly to the peculiar construction of the elements making up the burner and to the associated elements for supplying air and fuel thereto and for effecting combustion. The particular means and method for controlling the supply of fuel and air 85 is disclosed and claimed in the copending application Serial No. 457,874 filed May 31, 1930.

85 What applicants desire to claim is as follows:

1. A burner comprising a burner grating, a base plate for said grating having a pair of substantially semi-cylindrical openings therethrough positioned adjacent each other, an air supply conduit, and a pair of curved 110 hollow vaporizing members communicating with the openings in the base plate and with the air supply.

2. A burner comprising a burner grating, a base plate for said grating having a pair 115 of openings therethrough positioned adjacent each other, an air supply conduit, and a pair of oppositely curved hollow vaporizing members communicating with the openings in the base plate and with the air supply.

3. A burner comprising a burner grating, a base plate for said grating having a pair of substantially semi-circular openings therethrough positioned in a substantially circular area, an air supply conduit, and a pair 125 of oppositely curved hollow vaporizing members communicating with the openings in the base plate and with the air supply.

4. A burner comprising a burner grating, a base plate for said grating having a pair 130

of openings therethrough, an air supply conduit, and a pair of hollow vaporizing members communicating with the openings in the base plate and with the air supply conduit, 5 said members having substantially parallel portions communicating with the air conduit and oppositely curved portions communicating with the openings in the base plate.

5. A burner comprising a burner grating, 10 a base plate for said grating having a pair of openings therethrough, an air supply conduit, and a pair of hollow vaporizing members communicating with the openings in the base plate and with the air supply conduit, 15 said members having substantially parallel open end portions communicating with the air conduit and oppositely curved dead end portions, said portions being provided on their horizontal faces with openings for communicating with the openings in the base plate. 20

6. A burner comprising a pair of hollow question-mark shaped members positioned with their straight ends lying together, an air supply conduit communicating with said ends, the curved ends of said members lying in spaced relationship with openings on the upper horizontal faces, a burner base plate secured to the members and having openings 30 therethrough mating with the openings in the members, a burner grating secured to said base plate, and means for supplying air and fuel to said burner in regulated amounts.

7. A burner comprising a pair of hollow question-mark shaped members positioned with their straight ends lying together and substantially parallel, an air supply conduit communicating with the parallel ends of said members, the curved ends of said members lying in spaced relationship with openings on the upper horizontal faces, said openings being substantially semi-circular and lying in a substantially circular area, a burner base plate secured to the members and having openings therethrough mating with the openings in the members, a burner grating secured to said base plate, a pilot burner positioned under the hollow members whereby said members are initially heated, and means 45 for supplying air and fuel to said burners in regulated amounts. 50

In testimony whereof we affix our signature.
